UNITED STATES PATENT OFFICE

106,332

DESIGN FOR A COMBINED LAMP AND AIR CONDITIONER HOUSING

George Conwell Shipley, San Antonio, Tex., assignor of twenty-five per cent to Fred Turner, Jr., Midland, Tex.

Application February 11, 1937, Serial No. 67,595

Term of patent 3½ years

To all whom it may concern:

Be it known that I, George Conwell Shipley, a citizen of the United States, residing at San Antonio, in the county of Bexar and State of Texas, have invented a new, original, and ornamental Design for a Combined Lamp and Air Conditioner Housing, of which the following is a specification, reference being had to the accom-

panying drawing, forming part thereof, in which:

Figure 1 is a side elevational view of a combined lamp and air conditioner housing; and

Figure 2 is a top plan view thereof.

I claim:

The ornamental design for a combined lamp and air conditioner housing, as shown.

GEORGE CONWELL SHIPLEY.
